TRANSFORMER SWITCHING ARRANGE-
MENT

Harold R. Turner, Pittsfield, Mass., assignor to
General Electric Company, a corporation of
New York

Application October 9, 1934, Serial No. 747,520

18 Claims. (Cl. 171—119)

My invention relates to improvements in transformer switching arrangements and more particularly to improvements in arrangements for connecting transformers to feeders, grounding 5 transformers and feeders under predetermined conditions and changing the transformation ratio. An object of my invention is to provide an improved transformer switching arrangement which, with minimum space and insulating fluid 10 requirements, insures maximum safety and accessibility without greatly increased cost.

Transformers used in secondary network systems are usually placed in vaults which are frequently located in buildings. Such transformers 15 have been provided with junction boxes mounted on the outside of the transformer casing and the feeder connections led in through the floor of the vault to the junction box. The junction box contained the connections for the feeder, usually a 20 cable, and these connections were accessible only upon removal of the junction box cover and the insulating liquid. The junction box sometimes contained a switch for grounding the transformer under predetermined conditions. In order to prevent 25 operation of the grounding switch while the transformer is energized, an electromagnetically controlled lock was provided, the electromagnet being mounted either in the junction box or in the transformer where it was not only not readily 30 accessible but also was an electrical hazard. The transformers have also been provided with ratio adjusters. In order to prevent operation of the ratio adjusters while the transformer was energized, there has been provided over the ratio 35 adjusting switch handle a cover which could not be removed unless the grounding switch was in the grounding position. This arrangement was not entirely satisfactory because the ratio adjusting switch could be left in an off-tap position 40 and the grounding switch operated at will. Oil was used as an insulating and cooling fluid and the transformer and junction box required a large volume of oil. Obviously, the fire and explosion hazards placed many structural limitations 45 on both the location and construction of the vaults. These limitations were not conducive to either simplification of structure or convenience in location of the vaults.

In order to insure greater safety from explosions and fire, there has been developed a non-inflammable and non-explosive insulating liquid composed of certain halogenated hydrocarbons. But the cost of this is so much greater than the cost of oil as to render its use practically prohibitive in the prior transformer switching ar-

rangements because of the great volume of insulating liquid required by the transformer and junction box. In order to take advantage of the safety features of this insulating liquid with the greatest economy and simplification in structure, I provide, in accordance with my invention, an improved transformer switching arrangement in which the feeder connections, grounding switch and ratio adjusting switch are all mounted within the transformer, thereby eliminating the junction box and the space required by it in the vault, as well as the insulating liquid necessary to fill it. Further, by a more compact arrangement of parts, the volume of the transformer itself is reduced. Also in accordance with my 15 invention, I so arrange the feeder connections and the grounding switch as conveniently to arrange for bringing the feeder into the vault near the ceiling and as to be accessible for inspection and maintenance of those parts most likely to 20 need attention or renewal. I further provide a positive interlocking arrangement between the grounding switch and the ratio adjusting switch such that the latter must definitely be in one of its tap operating or switch closing positions 25 before the grounding switch can be operated. Moreover, I provide for the ratio adjusting switch a further improved locking means which is independent of the grounding switch mechanism. In order to reduce the electrical hazard 30 of the electromagnet for locking the grounding switch against operation while the transformer is energized, I provide an improved grounding switch actuating mechanism which is mounted on the outside of the transformer casing so as 35 to be isolated from the transformer proper and to be more conveniently accessible for inspection and maintenance.

My invention will be better understood from the following description when considered in connection with the accompanying three sheets of drawings, and its scope will be pointed out in the appended claims.

In the accompanying sheets of drawings, Fig. 1 represents in perspective, with part of the casing broken away, a transformer embodying my invention; Fig. 2 is a part perspective and a part diagrammatic illustration of a transformer switching arrangement embodying my invention as illustrated in Fig. 1; Fig. 3 is an elevation 45 illustrating how certain contacts of my switching arrangement may be removed for inspection and renewal; Fig. 4 is a perspective view partly in section illustrating the isolated phase contact mounting for the terminal and grounding con- 50 55

tacts of my switching arrangement; Fig. 5 is a perspective view with parts broken away illustrating my improved grounding switch actuating mechanism; and Fig. 6 is a plan view illustrating my improved arrangement for locking the ratio adjusting switch handle independently of the grounding switch mechanism.

Referring now particularly to Figs. 1 and 2, a liquid-immersed, self-cooled transformer is shown as having low-voltage windings 10, tapped high-voltage windings 11, a ratio adjusting switch 12, and also within the transformer casing 13, in accordance with my invention, a grounding switch 14, contact means 15 for line terminals 16 connected to the terminals of the high-voltage windings and engageable by the grounding switch 14, actuating means 17 for the grounding switch and interlocked therewith actuating means 18 for the ratio adjusting switch, 20 and electromagnetically controlled means 19 for preventing the closing of the grounding switch 14 while the transformer is energized. Further in accordance with my invention, for compactness, simplicity and accessibility, the contact means 15, the grounding switch 14 and the ratio adjusting switch 12 together with the actuating means for these switches are mounted on a suitable support such as the frame 9 within the casing 13, as more clearly shown in Figs. 1 and 3.

As shown, the contact means 15 comprises a pair of interconnected contacts for each phase of the circuit. Also as illustrated, the contacts 15 are of the segmental garter-spring socket type, the corresponding segments of each pair being interconnected by flexible leads 20 in such a way that the forces produced by the circuit currents tend to increase the contact pressure. In Fig. 2, for simplicity, only one lead 20 is shown for each phase, but it is to be assumed that there is an interconnecting lead for the corresponding segments of each pair, as shown more clearly in Fig. 4. For cooperating with each upper socket contact 15, the line terminals 16 are provided with plug contacts 21 which are suitably secured to the line feeder conductors 22, usually cables, and the insulation tapered to form a bushing, as shown in Fig. 3, in order to grade the voltage stresses. The line terminals 16 with the contacts 21 are insertable in the upper contacts 15 through openings 23 in the top of the transformer casing. These openings are closed and sealed by suitable end-bells 24 secured to a plate 25, as shown more clearly in Fig. 1. For cooperating with each of the lower contacts 16, the grounding switch 14 is provided with plug contacts 26 which are mounted on a suitably movable supporting member indicated as 14 which may be of metal and is grounded as shown.

In order that the contact means 15 of each phase may be suitably isolated and at the same time readily removable through the openings 23 in the top of the transformer for inspection and maintenance, they may be mounted in an insulating cylinder 27 which is removably secured to a supporting cylinder 28. This may be of insulating material suitably fastened to the frame 9, as shown more clearly in Fig. 4. In order that the contacts 15 may be readily removable the cylinder 27 may be provided with an inset metallic portion such as the threaded collar 29 which screws into a terminal ring 30 secured to the cylinder 28. The collar 29 is so secured to the collar 27, by lugs and pins as shown for example, as to prevent relative movement. Similarly, the terminal ring 30 is so secured to the cyl-

inder 28 as to prevent relative movement, for example by lugs and pins as shown, engaging a sleeve 31 which is rigidly secured to the cylinder 28. Each terminal ring 30 may be provided with a suitable stud connector 32 to which the high voltage windings 11 are connected. The segments of the contacts 15 are maintained in proper alignment and the contacts suitably spaced by sleeves 33, 34 and 35, which may be of insulation. The inner connectors 20 extend to the collar 29. The upper sleeve 35 may be secured to the cylinder 27 by pins as shown and may be tapered to fit the line terminal bushing. In order to remove the whole assembly within and including the cylinder 27, this cylinder may be provided with a metal collar 36 which is suitably secured to the cylinder 27 and provided with suitable means, such as notches 37, which are engageable by projections on a T-wrench 38 insertable through the openings 23 as shown in Fig. 3. It will thus be observable that the whole contact assembly is readily removable for inspection and repairs and that a whole new unit may be quickly substituted for one which has outlived its usefulness. In order that the grounding switch contacts 26 may likewise be readily removable, the supporting movable member 14 for these contacts may be made of metal and tapped to receive the lower threaded ends of the contacts 26. These contacts are provided with a suitable enlarged portion which is engageable by the head of a T-wrench 39 insertable through the openings 23. Thus any one of the contacts 26 can be readily removed and replaced without any necessity for taking the transformer apart.

As shown, the actuating means for the grounding switch comprises an operating member such as the crank 40 which is secured to the shaft 17, cranks 42 secured to the shaft 41, and links 43 interconnecting the cranks 42 with the movable contact supporting member 14 of the grounding switch. The member 14 is provided with guides 44 which slide in suitable guideways 45 in the frame 9.

In order to prevent operation of the grounding switch when open while the transformer is energized, I provide electromagnetically controlled means for preventing movement on the grounding switch actuating mechanism if the transformer is energized. As shown, this means comprises an electromagnet having its winding 46 connected to be energized in accordance with the voltage across one of the low voltage windings 10 and an armature 19 which is arranged to control the position of the locking member 47. This locking member is arranged to engage a recessed portion associated with the operating shaft 17. As long as the magnet winding 46 is energized to hold the locking member 47 in the locking position and the grounding switch is open, the crank 40 can not be turned in the direction of the arrow 48 to close the grounding switch. Upon deenergization of the magnet winding 46, the counterweighted armature 19 raises the locking member 47 to release the shaft 17 so that it can be rotated in the direction to close the grounding switch.

While the locking mechanism above described is generally satisfactory, it has the disadvantage of being completely within the transformer casing. It is therefore not conveniently accessible and the magnet winding introduces an electrical hazard which is not desirable. Accordingly, I prefer, in accordance with my invention, to use the operating handle mechanism shown in Fig. 75

5 because this mechanism is entirely self-contained and mounted exteriorly of the transformer. In this mechanism the crank or handle lever 40 is secured to a stub shaft 49 which 5 is bifurcated at the inner end to engage a suitably flattened portion, not shown, on the shaft 17. The stub shaft of each is provided with a projecting portion which may be in the form of a cam 50 so shaped as to be engaged by a locking member 51 mounted in the path of movement 10 of the cam to the end connected to be actuated in response to the movement of the armature 52 of the electromagnet 53. In Fig. 5, the locking member 51 is shown in the releasing position, for 15 clearness of illustration. This locking member is rotatively mounted in the frame 54 of the operating mechanism and for simplicity may be mounted to rock on its circular end portion in a correspondingly shaped socket in the frame. The 20 construction and arrangement of the parts is such that the locking member 51 is subjected only to compression when an attempt is made to turn the shaft in the direction of the arrow 55 while the magnet 53 maintains the locking member 25 raised into the locking position. The mechanism frame 54 is secured to the transformer casing 13 by suitable means, such as bolts 56, only one of which is indicated in Fig. 5. In order mechanically to lock the operating mechanism in 30 either one of its two positions, there may be provided a sliding bar lock 57 which is carried by the operating lever 40 and is arranged to engage holes 58 in the frame 54. Cooperating with the sliding bar lock 57 is an eye member 59 carried 35 by the operating lever 40, and a padlock inserted through the eye in this member and the eye in the member 57 serves to secure the switch in either of its two positions so that the switch cannot be operated while padlocked. The connecting lead 60 from the low voltage winding extends 40 through suitable insulation in the wall of the transformer casing 13 and thence through the frame to the electromagnet 53. It will accordingly be clear that with the mechanism so arranged 45 any faults in the winding of the electromagnet do not spread to the transformer and the whole mechanism is conveniently accessible without disturbing anything within the transformer.

50 The actuating mechanism for the ratio adjusting switch 12 comprises a crank such as a handle lever 61 secured to the shaft 18, a shaft 62 suitably geared to the shaft 18 and gears 63 and 64 for rotating the movable contacts 65 of 55 the ratio adjusting switch into any one of the various on-tap positions, three being shown for purposes of illustration. The contacts 65 may be mounted within insulating cylinders designated by the number 12 in Fig. 1. The handle lever 61 may, in accordance with my invention, include 60 an extension 66 which is retractable in the part 68 and, as shown in Fig. 6, a cover 67 provided with pockets or recesses 68 for so receiving one 65 end of the handle 66 that the ratio adjusting switch must be in a definite on-tap position before the cover 67 can be bolted in place against the side of the transformer casing 13, the bolt holes for the cover being so spaced as to permit 70 mounting the cover in only one way.

In order to prevent operation of the ratio adjusting switch 12 while the grounding switch is open, I provide a positive interlock between the actuating means of these switches, such that, 75 even when the grounding switch actuating mech-

anism is free to be operated, the ratio adjusting switch actuating mechanism must be left in a definite on-tap position before the grounding switch can again be operated. As shown, this interlocking feature comprises two interlocking 5 cams 70 and 71, respectively mounted on the shafts 18 and 41. The cam 70 is provided with notches 72, one for each on-tap position of the ratio adjusting switch for the free movement of the cam 71 but without movement of the cam 70. 10 Movement of the cam 70 is possible in the notch 73 in the cam 71 only when the grounding switch is in the grounding position.

Referring now to Fig. 2 for the operation of my invention, it will first be assumed that the transformer is energized and that the parts are positioned as shown. If now for any reason it becomes desirable to work on the transformer either for inspection, renewal of parts or changing the tap setting, it will first be necessary to deenergize the transformer in order to release the lock 47 on the actuating mechanism of the grounding switch. The transformer is deenergized by opening the circuit breaker in the feeder 22 at the supply station and opening the network circuit breaker on the low voltage side of the transformer. The network circuit breaker and its associated relay mechanism may be mounted in a casing 75 secured to the transformer, as shown in Fig. 1. As soon as the transformer is deenergized, the electromagnet 46 no longer retains its armature 19 and the adjustably mounted counterweight 76 thereon raises the locking member 47 from its recess on the shaft 17. The operating crank 40 may then be turned in the direction 80 of the arrow 48 to close the grounding switch. When the grounding switch is closed, the notch 73 on the shaft 41 is in the plane of the cam 70 and the shaft 18 so that the actuating mechanism of the ratio adjusting switch can be operated 85 upon removal of the cover 67. Accordingly, the tap position may be varied, but in any case some one of the notches 72 must be definitely positioned in the plane of the cam 73; otherwise, it will not be possible to open the grounding switch. 90 If it is desired to examine the contacts 15 or the contacts 26 of the grounding switch, these may be removed in the manner heretofore described and repaired, if found necessary, or new ones 95 substituted. It is to be noted that all this can be done without material disturbance to the transformer, since it is merely necessary to remove the end bells 24 and the plate 25 in order to gain access to the contacts 15 and 26.

While I have shown and described my invention in considerable detail, I do not desire to be limited to the exact arrangements shown, but seek to cover in the appended claims all those modifications that fall within the true spirit and scope of my invention.

What I claim as new and desire to secure by Letters Patent of the United States, is:

1. In combination with a transformer and a casing therefor, a switch within said casing operative in one position to ground the high voltage winding of the transformer and means for actuating said switch mounted on the outside of said casing and including an operating shaft extending through said casing and means for preventing movement of said shaft in a direction to move the switch to the grounding position while the transformer is energized including an electromagnet connected to be energized from the transformer, a projection 65 on said shaft, a locking member mounted for 70

movement in the path of movement of said projection and engageable thereby under compression when the shaft is turned in a direction to move the switch to the grounding position while 5 the electromagnet is energized.

2. In combination with a transformer and a casing therefor, switching means within said casing operative in one position to ground a winding of the transformer and means for actuating said switching means mounted exteriorly of said casing and including electromagnetically controlled means energized from the transformer for preventing actuation of the switching means 10 to the grounding position while the transformer 15 is energized.

3. In combination with a transformer and a casing therefor, a switch within said casing operative in one position to ground the high voltage winding of the transformer and means 20 for actuating said switch mounted on the outside of said casing and including an operating member and means for preventing movement of said member in a direction to move the switch to the grounding position when the transformer 25 is energized, including an electromagnet connected to be energized from a low-voltage winding of the transformer.

4. In combination with a transformer and a casing therefor, a grounding switch within said 30 casing, an operating mechanism for said grounding switch mounted exteriorly of said casing and comprising a shaft, and means for preventing rotation of said shaft under a predetermined condition of the transformer including a projection 35 on said shaft, a member movable in the plane of rotation of said projection and engageable thereby only under compression when the shaft is turned in one direction and the member is in a predetermined position and electromagnetically 40 controlled means for moving said member into said position connected to be energized from the transformer.

5. In combination with a polyphase transformer and a casing therefor, a frame mounted 45 within said casing and switching means mounted on said frame and comprising an isolated pair of interconnected contacts for each phase, each pair being respectively connected to a phase winding of the transformer, phase conductor terminal 50 contacts respectively engageable with one of the contacts of each of said pairs, a grounding switch comprising a movable bridging member of conducting material connected to ground, a contact for each phase mounted on said member 55 and means for actuating said member to move the contacts mounted thereon into engagement with the other contact of said pairs whereby to ground the transformer windings connected thereto and said conductor terminals.

6. In combination with a polyphase transformer and a casing therefor, a frame mounted within said casing and switching means mounted on said frame and comprising an isolated pair of interconnected contacts for each phase, each pair 60 being respectively connected to a phase winding of the transformer, phase conductor terminal contacts respectively engageable with one of the contacts of each of said pairs, a grounding switch comprising a movable member, a contact for each phase mounted on said member and grounded and means for actuating said member to move the contacts mounted thereon into engagement with the other contacts of said pairs whereby to ground the transformer windings connected thereto and said conductor terminals.

7. In combination with a polyphase transformer and a casing therefor, a frame mounted within said casing and switching means mounted on said frame and comprising an isolated pair of interconnected contacts for each phase, each pair 5 being respectively connected to a phase winding of the transformer, phase conductor terminal contacts respectively engageable with one of the contacts of each of said pairs, a grounding switch comprising a movable bridging member of conducting material connected to ground, a contact for each phase mounted on said member, means for actuating said member to move the contacts mounted thereon into engagement with the other contact of said pairs whereby to 10 ground the transformer windings connected thereto and said conductor terminals, means for preventing movement of said member while the transformer is energized, a ratio adjusting switch connected to the transformer windings which are 15 connected to the pairs of contacts, means for actuating said ratio adjusting switch and means interlocking the actuating means for said member and the actuating means for said ratio adjusting switch for permitting actuation of the 20 ratio adjusting switch only when the grounding switch is in the grounding position.

8. In combination with a polyphase transformer and a casing therefor, a frame mounted within said casing and switching means mounted on said frame and comprising an isolated pair of interconnected contacts for each phase, each pair being respectively connected to a phase winding of the transformer, phase conductor terminal contacts respectively engageable with one of the 30 contacts of each of said pairs, a grounding switch comprising a grounded movable contact for each phase, means for actuating said movable contacts into engagement with the other contact of said pairs whereby to ground the transformer 35 windings connected thereto and said conductor terminals, means for preventing movement of said grounding switch contacts while the transformer is energized, a ratio adjusting switch connected to the transformer windings which are connected 40 to the pairs of contacts, means for actuating said ratio adjusting switch and means interlocking the actuating means for said grounding switch contacts and the actuating means for said ratio adjusting switch for permitting actuation of the 45 ratio adjusting switch only when the grounding switch contacts are in the grounding position.

9. In combination with a transformer and a casing therefor, switching means mounted within said casing and comprising a pair of interconnected contacts connected to a winding of the transformer, a conductor terminal contact insertable through said casing and engageable with one contact of said pair, a switch comprising a movable contact connected to ground and means for 60 actuating said movable contact into engagement with the other contact of said pair whereby to ground the transformer winding connected thereto and said conductor terminal, means for preventing movement of said movable contact while the transformer is energized, a ratio adjusting switch comprising actuating means therefor and means interlocking the actuating means for said movable contact and the actuating means for said ratio adjusting switch for permitting actuation of the 65 ratio adjusting switch only when the movable contact is in engagement with the other contact of said pair.

10. In combination with a transformer and a casing therefor, switching means mounted within 70

5 said casing and comprising a pair of interconnected contacts connected to a winding of the transformer, a conductor terminal contact insertable through said casing and engageable with one contact of said pair, a switch comprising a movable contact connected to ground and means for actuating said movable contact into engagement with the other contact of said pair whereby to ground the transformer winding connected there-
10 to and said conductor terminal contact.

11. In combination with a transformer and a casing therefor, switching means mounted within said casing and comprising contact means connected to a winding of the transformer, a terminal contact insertable through said casing and engageable with said contact means, a switch comprising a movable contact connected to ground and means for actuating said movable contact into engagement with said contact means whereby to ground the transformer winding connected thereto and said terminal contact.

12. In combination with a transformer and a casing therefor, a readily removable housing supported within said casing and withdrawable through an opening therein, contact means carried by said housing, a terminal contact insertable through said casing opening to engage said contact means, a readily removable contact movably supported within said casing and engageable upon a predetermined movement in one direction with said contact means and means for removing said movable contact through said casing opening.

13. In combination with a transformer and a casing therefor, a readily removable insulating housing supported within said casing and withdrawable through an opening therein, two interconnected socket contacts carried by said housing, a plug contact insertable through said casing opening to engage one of said socket contacts, a readily removable plug contact movably supported within said casing and engageable upon a predetermined movement in one direction with the other of said socket contacts and means for removing said movable plug contact through said casing opening subsequently to the removal of said housing.

14. In combination with a transformer and a

casing therefor, readily removable contact means supported within said casing and withdrawable through an opening therein, a terminal contact insertable through said opening to engage said contact means, a readily removable contact movably supported within said casing and engageable with said contact means on a predetermined movement in one direction and means for removing said movable contact through said casing opening subsequently to the removal of said contact means.

5

15. In combination with a transformer and a casing therefor, a readily removable socket contact means supported within said casing and withdrawable through an opening therein and a cooperating plug contact insertable through said casing opening to engage said socket contact means.

16. In combination with a transformer and a casing therefor, a readily removable socket contact means supported within said casing and withdrawable through an opening therein, a cooperating plug contact insertable through said casing opening to engage said socket contact means, and a readily removable plug contact means re-
25 movably supported within said casing substantially in alignment with said cooperating socket and plug contact means and engageable with the socket contact means upon a predetermined movement in one direction.

30

17. In combination with a transformer and a casing therefor having a cover provided with an opening, a readily removable socket contact means insertable through said cover opening and supported within said casing, and a cooperating plug contact insertable through said cover opening to engage said socket contact means.

18. In combination with a transformer and a casing therefor, readily removable contact means supported within said casing and withdrawable through an opening therein, a contact readily removable through said opening movably supported within said casing and engageable with said contact means on a predetermined movement in one direction, and means for effecting the movement of said movable contact.
